BURGLAR ALARM CONTROL HOUSING

Anthony P. Montalbano, 29 Hitching Post Lane,
Glen Cove, N.Y. 11542

Filed Aug. 29, 1974, Ser. No. 501,490

Term of patent 14 years

Int. Cl. D10—06

U.S. Cl. D10—121

FIG. I.

FIG. 2.

FIG. 3.

FIG.4.

FIG.5.

FIG.6.

FIG.7.

FIG. 1 is a perspective view of a burglar alarm control housing embodying my design;

FIG. 2 is a front elevational view of the burglar alarm control housing of FIG. 1;

FIG. 3 is a rear elevational view of the burglar alarm control housing of FIG. 1;

FIG. 4 is a bottom plan view of the burglar alarm control housing of FIG. 1;

FIG. 5 is a top plan view of the burglar alarm control housing of FIG. 1;

FIG. 6 is a right side elevational view of the burglar alarm control housing of FIG. 1; and

FIG. 7 is a left side elevational view of the burglar alarm control housing of FIG. 1.

I claim:

The ornamental design for a burglar alarm control housing, as shown and described.
